UNITED STATES PATENT OFFICE.

JAMES W. HAMILTON AND WILLIAM GWINNUP, OF INDIANAPOLIS,
INDIANA.

FENCE-POST.

No. 841,777.

Specification of Letters Patent.

Patented Jan. 22, 1907.

Application filed October 19, 1905. Serial No. 283,558.

To all whom it may concern:

Be it known that we, JAMES W. HAMILTON and WILLIAM GWINNUP, citizens of the United States, residing at Indianapolis, in the county of Marion and State of Indiana, have invented certain new and useful Improvements in Fence-Posts, of which the following is a specification, reference being had therein to the accompanying drawings.

10 This invention relates to improvements in fence-posts constructed of artificial stone or like material, such as a composition of cement or concrete, and is particularly constructed for use in connection with rail fences, as will be hereinafter more fully described, and particularly pointed out in the claims.

15 The object of this invention is to provide a fence-post with suitable pockets or hangers oppositely situated on the opposite sides of the post for supporting the rails of the fence and which pockets or hangers are constructed so that rails of the fence may be readily removed and replaced. We attain these objects by means of the fence-post illustrated in the accompanying drawings, in which similar numerals of reference designate like parts throughout the several views.

20 Figure 1 is a front elevation of our invention of a fence-post, showing the removable rails thereof. Fig. 2 is a side view of the same, taken through the line A. B. (See Fig. 1.) Fig. 3 is a detail view of one of the rail-supporting pockets looking in the direction of the arrow a. (See Figs. 1 and 4.) Fig. 4 is a similar detail view of the same, taken through the line C D, (see Fig. 3;) and Fig. 5 is a detail diagram view of a strip of metal cut to the required width of the wire-25 supporting pocket or hanger shown in light lines where the metal is to be creased or bent into form.

25 The post 1 is preferably composed of concrete or some other mixture of cement and is preferably made rectangular in cross-section, with a larger base end, and the same is regularly tapered on its sides from its base to its top reduced or smaller end.

30 Along each side of the post 1 are arranged in vertical alinement the pockets or hangers

2, wherein the ends of the rails 3 are removably fitted and supported to be removable therefrom. The pockets 2 are situated on and removably secured to the opposite sides of said post 1 by the securing-bolts 4. 55

The rail-supporting hangers or pockets 2 are each composed of a single strip of metal bent into form and have their base or connecting portions 2^a, the opposing parallel vertical sides 2^b, the folds 2^c, and the overlapping feet ends 2^d. The folds 2^c are each folded diagonally, as shown in dotted lines, to cause the overlapping feet ends 2^d to assume the position shown in dotted lines. (See Fig. 5.) The sides 2^b are then folded 60 on the creases 8 till the sides 2^b are parallel. The overlapping feet ends 2^d are then folded back or inwardly and at right angles to the faces of the sides 2^b to lap one above the other to cause the bolt-holes 9 to register, as 65 shown in Fig. 3.

Having thus fully described this our invention, what we claim as new and useful, and desire to cover by Letters Patent of the United States therefor, is— 70

1. In a rail fence, the combination with a fence-post composed of artificial stone or cement, of a series of rail-supporting pockets or hangers composed of single strips of metal bent and folded into form, said pockets or 75 hangers removably secured to the opposite sides of said post and arranged in vertical alinement at suitable intervals apart.

2. In a rail fence, the combination with a fence-post composed of artificial stone or cement, of a series of rail-supporting pockets or hangers composed of a single strip of metal bent and folded into rectangular form, said pockets or hangers arranged in opposing pairs and securing-bolts passing through said 80 post to project from the opposite sides thereof and each bolt situated to support a single opposing pair of pockets or hangers. 85

In testimony whereof we affix our signatures in presence of two witnesses.

JAMES W. HAMILTON.
WILLIAM GWINNUP.
